CLAIM

We claim the ornamental design for a digital satellite receiver cover, as shown and described.

DESCRIPTION

FIG. 1 is a front perspective view of the enclosure for a digital satellite receiver cover;

FIG. 2 is a front view thereof;

FIG. 3 is a rear view thereof;

FIG. 4 is a top view thereof;

FIG. 5 is a left side view thereof;

FIG. 6 is a right side view thereof;

FIG. 7 is a bottom view thereof;

FIG. 8 is another front perspective view thereof;

FIG. 9 is a back perspective view thereof;

FIG. 10 is another back perspective view thereof;

FIG. 11 is a front view of a part of the main bezel of the digital satellite receiver cover, prior to assembly of a speaker component and floating bezel to the main bezel portion of the digital satellite receiver cover;

FIG. 12 is a partially exploded view of the satellite receiver cover, depicting the speaker component and floating bezel for assembly to a main bezel portion of the otherwise assembled digital satellite receiver cover;

FIG. 13 is a partial top perspective view thereof;

FIG. 14 is a partial front perspective view thereof;

FIG. 15 is another partial top perspective view thereof; FIG. 16 is a partially disassembled front perspective view thereof, with the floating bezel shown prior to assembly to the speaker component assembled to the digital satellite receiver cover;

FIG. 17 is a front view of the floating bezel; and,

FIG. 18 is a front view of the dial inserted behind the main bezel part shown in FIG. 11.
